PRESS CONTROL MECHANISM

Joseph P. Daly, Minneapolis, Minn., assignor to
The American Laundry Machinery Company,
Cincinnati, Ohio, a corporation of Ohio

Application May 13, 1933, Serial No. 670,957

10 Claims. (Cl. 121—38)

This invention relates to garment pressing machines, and more particularly to the control mechanism therefor. The object of the invention is to provide improved mechanism by which the movements of the pressing members toward and from each other for both the closing and final pressure operations are controlled in a simple manner and with due regard for safety of the operator and safeguarding of the press mechanism.

A further object of the invention is to provide control mechanism of this kind in which the press is operated by a fluid pressure motor of servo-motor type controlled by a primary valve or valve mechanism which in turn is actuated or controlled by a relay device under the direct control of the operator, preferably by two-hand control mechanism, the press also including interlocking or interrelated parts actuated or controlled by the servo-motor and by the relay device, for the purpose of preventing the actuation of the servo-motor under full power pressure unless the press has been first fully closed to a safe position and in a manner to prevent any possibility of the operator's hands being between the pressing members or in a dangerous position.

A further object of the invention is to provide press control mechanism of this kind including primary valve mechanism actuated by a relay device subject to the operation of secondary valves or valve mechanism, which, in turn, control the flow of pressure to the relay device from a reservoir or container of limited capacity sufficient for only a single operation of the relay device, thereby preventing false or faulty manipulation such as might endanger the operator.

Further objects of the invention are in part obvious and in part will appear more in detail hereinafter.

In the drawing, which represents one suitable embodiment of the invention, Fig. 1 is a sectional elevation, partly diagrammatic, showing the servo-motor and its control devices, with the parts in release or "press-open" position; Figs. 2 and 3 are detail sectional views on the lines 2—2 and 3—3 of Fig. 1, and showing the valve ports and passages; Fig. 4 is a view corresponding to Fig. 1 and showing the parts in full pressure position; Figs. 5 and 6 are views corresponding to Figs. 2 and 3 respectively, and illustrating the positions of the valves corresponding to Fig. 4; Fig. 7 is a detail rear elevation showing the primary valve mechanism; Fig. 8 is a side elevation from the right in Fig. 7; and Figs. 9 and 10 are cross sectional views on the lines 9—9, 10—10,

respectively, of Fig. 8, and showing the valve ports and passages in positions corresponding to Fig. 1; and Figs. 11 and 12 are similar views, showing the ports and passages in the positions corresponding to Fig. 4.

While the control mechanism described may be employed for operating any kind of device actuated by a fluid pressure motor of servo type, the drawing shows the invention applied to a garment press illustrated more or less conventionally and including a frame 1 carrying a stationary lower pressing member or bed 2 cooperating with an upper pressing member or head 3 carried by one arm 4 of a lever pivoted on the frame at 5, the rear arm of said lever being actuated by upper and lower toggles 6, 7, to one of which, such as to the lower toggle member, is pivotally connected the rod 8 of a piston 9 working in the chamber 10 of a fluid pressure cylinder 11, said chamber communicating with a conduit 12 by which pressure fluid is introduced into and exhausted from the pressure end of the chamber.

The flow of pressure fluid to and from said chamber is controlled by primary valve mechanism or devices marked generally 13 in Figs. 1 and 4 and illustrated in detail in Figs. 7 to 12 inclusive. This valve mechanism, generally speaking, is of gas cock type including a rotatable and usually tapered plug turning in a casing and having ports controlling two separate 30 passages through the plug and casing, one of said passages being for the supply and the other for exhaust. The primary valve is actuated or controlled by a relay device, marked generally 14 in Figs. 1 and 4 and which, in the form shown, 35 is a fluid pressure piston and cylinder device to which pressure fluid is supplied from a reservoir 15, having capacity for storing sufficient fluid, at supply pressure, for one operation only of said relay device, the pressure supply to which 40 comes from a pipe 16 communicating with a suitable source of fluid under pressure, such as a pump, a large tank or supply reservoir or the like, not shown. The flow of pressure fluid from the source to the reservoir and from the reservoir to the relay device is controlled by secondary valve devices, two of which are shown, marked 17, 18 and each of which, generally speaking, is of the same form and arrangement as the valve 13 shown in Figs. 7, 8, etc.

Referring first to the secondary control valves, each includes a casing 19 in which rotates a plug 20, preferably tapered and held to its seat by a compression spring 21. At the opposite end of the plug its stem is provided with an operat-

ing handle 22 and the plug is subject to the torque of a spring 23, which normally holds it in the position shown in Figs. 2 and 3. Each plug simultaneously controls the flow of pressure fluid through two conduits, to-wit, the conduit 16 connecting the reservoir 15 to the supply source, and the ports and passages for which are shown in Fig. 2, and the conduit 16a connecting the reservoir 15 with the chamber of the relay cylinder 14, and the ports and passages for which are shown in Fig. 3. In the normal position, shown in Figs. 2 and 3, the fluid supply is in open communication with the reservoir 15, as in Fig. 2, and communication from the reservoir 15 to the relay cylinder 14 is cut off by a lapped port of the left hand valve plug and the cylinder 14 is open to exhaust at 24. Indeed, both plugs open to exhaust on the same relay cylinder side.

Assuming the parts in the position shown in Figs. 1 to 3, if the operator applies his two hands to the levers of the two valves 17, 18 and moves them both outwardly to the position shown in Fig. 4, the left hand valve-plug being turned clockwise and the right hand plug counterclockwise, the valve plugs move to the positions shown in Figs. 5 and 6, thereby cutting off communication of the reservoir 15 with the source of fluid supply and opening up communication from said reservoir to the cylinder 14. Thereupon the piston 14a in said cylinder moves over to the position shown in Fig. 4, the cylinder itself being pivoted at 14b to a bracket carried by cylinder 11. The rod 14c of said piston is pivotally connected at 25 to the outer end of an arm 26 attached to the stem of the plug of the valve 13. As a consequence said valve is moved from the position shown in Figs. 9 and 10 to the position shown in Figs. 11 and 12, with an effect now to be described.

Conduit 12, communicating with the servomotor cylinder chamber 10, has two branches both controlled by the valve 13. One branch 12a communicates with a suitable source of pressure fluid supply which may be the same or a different source from that with which the pipe 16 communicates. The other branch 12b communicates with exhaust, such as through the muffler 27.

In the normal or "press-open" position, shown in Figs. 1, 11 and 12, the cylinder chamber 10 communicates with exhaust by way of the conduit 12b, which is open through the primary valve 13. The fluid supply to the chamber 10 through conduit 12a is, however, closed at the valve 13. When the relay device moves the valve 13 to the position shown in Fig. 4 its ports and passages assume the positions shown in Figs. 9 and 10, with the pressure fluid supply pipe 12a now open to the pipe 12 and the exhaust through pipe 12b being cut off. Pressure fluid now flows from the source into the chamber 10 and the piston 9 promptly moves over to the right in Fig. 1 thereby moving the head toward the bed or, in other words, closing the press.

To secure such action it is necessary to actuate both of the valve handles 22, thereby compelling the operator to use both hands and preventing him from putting one hand between the pressing members. Moreover, the capacity of the reservoir 15 is limited to an amount sufficient, at supply pressure, for one actuation only of the piston of the relay device 14. Therefore, if the operator takes one hand off from one of the valves 17, 18 before the closing operation is completed, the relay cylinder 14 is evacuated and

a second operation of the handle of the valve which was released will not produce a second complete operation of the relay device, but it is necessary to permit both valve handles to recede to the normal positions for a full recharge of the reservoir 15 before the press can again be operated.

One of the parts of the mechanism actuated by the servo-motor piston 9 is utilized to actuate a part controlled by the relay device 14, to produce interaction or interrelation between the two operations. Specifically, a part of the piston rod 8, such as the swivel or head 28 thereof, has pivoted thereto at 29 an arm 30 capable of adjustment by the set screws 31, 32. The upper end 15 of said arm has a perforated ear 33 through which slides a rod 34 which in turn is slidable through a block 35 slidable in guideways in a support 36 carried by any suitable part, such as by the wall of cylinder 11. The block 35 at one end is 20 provided with a shoulder 37 and its upper face is provided with a concave recess or seat 38 to receive a segment 39 attached to the end of the plug of the valve 13, as shown in Figs. 7 and 8. The plug of this valve also carries a pin 40, the 25 opposite ends of which engage shoulders at the sides of a lug 41 of the casing, which shoulders serve as stop abutments to limit valve rotating motion.

As shown in Fig. 1 that end of cylinder 14 30 through which the rod 14c slides, may consist of a thimble-like cap 14d adjustably threaded upon the cylinder body and held in adjusted position by a set screw 14e. This cap may be adjusted to any position where it will serve to limit 35 piston motion to the right amount to properly operate valve 13, as will be readily understood.

Rod 34 may have limited lost sliding motion through the slide or block 35, for which purpose it is provided with two sets of lock nuts 42, 43 40 located at opposite ends of said block. Also, perforated ear 33 has lost sliding motion with reference to the rod 34, such motion being limited by a set of lock nuts 44 adjustably secured near the outer end of the rod and a compression spring 45 45 lying adjacent another pair of adjustable lock nuts 46.

When the press is closed by actuation of primary valve 13 by the relay device 14, as before described, the arm 30 moves with the piston rod 8 and slides along the rod 34 until it engages the lock nuts 44. Thereupon additional motion of the piston moves the rod 34 until the lost motion between lock nuts 42 and block 35 is taken up, whereupon the block 35 moves to the right 50 or to the position shown in Fig. 4. In said position a blank or flat face 47 of the slide lies opposite to or beneath the position formerly occupied by the segment 39 and therefore forms an abutment or obstacle which prevents the segment 39 from returning to its former position and thereby locks the primary valve 13 in its "pressure-on" position. Locking of the valve 13 in "pressure-on" position of course actually occurs before the block 35 reaches its extreme 60 right-hand position, shown in Fig. 4. It actually occurs just as soon as the first increment of the flat face 47 of the slide moves into the path of return movement of the segment 39, as will be readily understood.

The parts are so adjusted, by adjustment of the lock nuts described, that the block 35 does not assume its position locking valve 13 until the press has been fully closed to a safe position in which it is impossible for the operator to get 75

his hands, arms or any part of his person between the pressing members. If the operator takes his hands off from one or both of the secondary valve levers 22 at any time before the block 35 reaches its locking position, valve 13 is returned by the tension spring 48 to its normal or "press-open" position, opening chamber 10 to exhaust through the pipe 12b, and the pressing members are thereupon opened immediately by the counter-balancing springs 49 or counter-weight, not shown, or both.

Assuming, however, that the hands are held on the control levers 22 until the block 35 reaches its locking position, in which the pressing members are safely closed, the operator can now take his hands off from the valve levers 22 and pressure fluid will continue to flow into the chamber 10, building the pressure therein up to the value of the main supply pressure fluid or of any pressure reducing or controlling valve which may be employed. Usually the rate of flow of pressure to the chambers of each of the cylinders 11 and 14 is controlled by adjustable needle or other throttle valves illustrated conventionally at 50, although this is not essential.

Of course, it will be understood that in the initial set-up the press controlled parts are adjusted, by adjustment of the position of the lock nuts 44, 42, so that locking position of the block 35 is reached only when the pressing members are in safe closing position, as described.

With the press parts closed in full pressure position, as described, the press remains closed for as long a period as the operator may desire and the operator is free to step away and operate or control another press or do other work, as may be desirable. When it is desired to open the press the operator actuates a suitable releasing device, such as the handle 51 of a simple valve 51a in a conduit 52 communicating with the chamber 10, such as by connection to the pipe 12 at the point 53. The valve handle 51 may be connected to a foot treadle or may be located in any suitable position convenient for operation by the knee or by the hands of the operator, as may be preferable. When it is actuated it provides free flow to exhaust from the chamber 10, and such exhaust evacuates said chamber and permits the pressing members to open and return to the position shown in Fig. 1. In so doing the toggle members 6, 7 also return to initial position and the piston 9 moves over to the left, thereby causing the perforated ear 33 to travel along rod 34 until it engages the spring 45, whereupon the rod 34 is moved to the left and as soon as the lock nuts 43 engage the block 35 said block also moves to the left until its shoulder 37 engages the guide 36, in the position shown in Fig. 1. As soon as blank portion 47 of the block 35 passes wholly beyond the zone of movement of the segment 39, the spring 48 returns lever 13 to its initial position, which opens a permanent exhaust from the chamber 10 by way of the pipe 12b, and the operator can release the temporary exhaust lever 51, which returns to its initial position under the influence of a spring or the like, not shown.

The press parts are now ready for another cycle of similar operations.

It is, of course, obvious that, assuming the parts shown in the position, Fig. 1, if the operator applies his hand to the head or head lever and manually closes the pressing members, the piston 9 will move to the right or to approximately the position shown in Fig. 4. However, valve 13 has not been moved because the release cylinder 14

is open to exhaust. As a result, the parts of valve 13 and of block 35 are in the position shown in Fig. 7 and the segment 39 therefore serves as an obstacle to prevent complete movement of block 35 to the right and it is therefore also impossible to move the piston 9 completely to the right. In other words, if the operator closes the press manually, it is impossible to apply full power pressure to the pressing parts unless the same cycle of control operations is followed, by applying both hands to the lever 22 and actuating the relay device 14 which in turn moves the primary valve 13 to "pressure-on" position, with results as before.

The limited lost motion of rod 34 in block 35 is not essential, but may be resorted to as an expedient to prevent mechanical interference between the right hand end of rod 34, as shown in the drawing, and the toggle mechanism 6, 7 or other moving parts of the press, which, of course, are shown conventionally in the drawing and not necessarily in their true relation to the rod 34.

The control mechanism described is simple in operation and provides fully protected two-hand control mechanism by which the press may be controlled and actuated in the desirable way but nevertheless with full safety for the operator and safeguarding of the press against faulty operation or injury to its parts.

What I claim is:

1. Apparatus of the character described, comprising a device to be operated, an operating fluid pressure servo-motor therefor, and controlling means for said motor, comprising a source of pressure fluid supply, primary inlet and exhaust valve means controlling the connection of said motor either to said source or to exhaust, a fluid pressure relay motor connected to operate said valve means, a reservoir having capacity for storing sufficient fluid, at supply pressure, for one operation only of said relay motor, and two hand control means controlling the connection of said reservoir to a source of pressure fluid or to said relay motor and of said relay motor to exhaust.

2. Apparatus of the character described, comprising a device to be operated, an operating fluid pressure servo-motor therefor, and controlling means for said motor, comprising a source of pressure fluid supply, primary inlet and exhaust valve means controlling the connection of said motor either to said source or to exhaust, a fluid pressure relay motor connected to operate said valve means, a reservoir having capacity for storing sufficient fluid, at supply pressure, for one operation only of said relay motor, and secondary valve means normally establishing connection of said reservoir to a source of pressure fluid and of said relay motor to exhaust, said secondary valve means being operable to close the connection of said reservoir to the source and of said relay motor to exhaust and to open communication between said reservoir and relay motor.

3. Apparatus of the character described, comprising a device to be operated, an operating fluid pressure servo-motor therefor, and controlling means for said motor, comprising a source of pressure fluid supply, primary inlet and exhaust valve means controlling the connection of said motor either to said source or to exhaust, a fluid pressure relay motor connected to operate said valve means, a reservoir having capacity for storing sufficient fluid, at supply pressure, for one operation only of said relay motor, two hand control means controlling the connection of said

- reservoir to a source of pressure fluid or to said servo-motor therefor, and controlling means therefor, comprising a source of pressure fluid supply, valve means controlling the connection of said motor either to said source or to exhaust, a fluid pressure actuated relay motor for operating said valve means, a reservoir having capacity for storing sufficient fluid, at supply pressure, for one operation only of said relay motor, two conduits, one for supplying pressure fluid from said source to said reservoir and the other for supplying pressure fluid from the reservoir to the relay motor to control the servo-motor operation, and two valve members for operation respectively by the two hands of the operator, each of said valve members controlling the flow through both of said conduits. 5
4. Apparatus of the character described, comprising a device to be operated, an operating fluid pressure servo-motor therefor, and controlling means for said motor, comprising a source of pressure fluid supply, primary inlet and exhaust valve means controlling the connection of said motor either to said source or to exhaust, a fluid pressure relay motor connected to operate said valve means, a reservoir having capacity for storing sufficient fluid, at supply pressure, for one 10 operation only of said relay motor, secondary valve means normally establishing connection of said reservoir to a source of pressure fluid and of said relay motor to exhaust, said secondary valve means being operable to close the connection of said reservoir to the source and of said relay motor to exhaust and to open communication between said reservoir and relay motor, and means independent of said primary exhaust valve 15 for evacuating the pressure fluid in said servo-motor. 15
5. Apparatus of the character described in claim 1, in which said primary valve means is provided with yielding means for normally maintaining it in servo-motor exhaust position. 20
6. Apparatus of the character described in claim 1, in which said primary valve means is provided with yielding means for normally maintaining it in servo-motor exhaust position, and 25 cooperating means actuated respectively by said servo-motor and relay motor for locking said primary valve means in servo-motor supply position when the device to be operated reaches safe position. 30
- 40 7. Apparatus of the character described, comprising a device to be operated, an operating
8. Apparatus of the character described in claim 7, including exhaust means independent of said relay motor for evacuating the pressure of said servo-motor. 20
9. Apparatus of the character described, comprising a cylinder and piston motor, and controlling means therefor including a source of pressure fluid supply, a reservoir having capacity for storing sufficient fluid at supply pressure for one 25 operation only of said motor, a conduit communicating between said source and said reservoir, a second conduit communicating between said reservoir and said motor, and two valve members spaced apart for operation respectively by the two hands of an operator, each of said valve members controlling the flow through both of said conduits. 30
10. Apparatus as described in claim 9, in which the valve members in the second conduit have flow and exhaust ports communicating with the conduit leading to said motor, and the said valve members are biased in cylinder-exhausting position. 35

JOSEPH P. DALY. 40
